(57) **CLAIM**

The ornamental design for a fixture, as shown and described.

DESCRIPTION

FIG. 1 is a perspective view of the present invention. FIG. 2 is a front view of the invention shown in FIG. 1. FIG. 3 is a back view of the invention shown in FIG. 1. FIG. 4 is a right view of the invention shown in FIG. 1. FIG. 5 is a left view of the invention shown in FIG. 1. FIG. 6 is a top view of the invention shown in FIG. 1; and, FIG. 7 is a bottom view of the invention shown in FIG. 1. The broken lines shown in the Figures are for environmental purposes only and form no part of the claimed fixture.
